UNITED STATES PATENT OFFICE

DAVID S. JACOBUS, OF MONTCLAIR, NEW JERSEY, ASSIGNOR TO THE BARCOCK & WILCOX COMPANY, OF BAYONNE, NEW JERSEY, A CORPORATION OF NEW JERSEY

HEAT TRANSFER DEVICE

Original application filed September 4, 1918, Serial No. 252,550. Divided and this application filed June 20, 1929. Serial No. 372,269.

This invention relates to a novel and improved form of heat transfer device, and is a division of my copending application Serial No. 252,550, filed September 4, 1918, which has matured into Patent No. 1,729,259, dated September 24, 1929. The novel features of the invention will be best understood from the following description and the annexed drawings, in which

10 Fig. 1 is a vertical sectional view through an economizer constructed according to the invention.

Fig. 2 is a sectional view of the structure shown in Fig. 1, and taken approximately 15 on the line 2—2 of Fig. 1.

Fig. 3 is a fragmentary sectional view on an enlarged scale, showing the relation of the headers at one end of the tubes.

Fig. 4 is a fragmentary sectional view 20 taken approximately on the line 4—4 of Fig. 3.

For the purposes of illustration, I have shown the invention as applied to an economizer 1 disposed above a boiler having two 25 steam and water drums 2 and 3, from which hot gases pass upwardly through flues 4 and 5. Disposed in the flue 4 is the economizer and the hot gases after passing over the tubes of the economizer are drawn outwardly as by a fan 6 and discharged through a flue 7. A similar arrangement may be used in the flue 5.

The economizer comprises a plurality of tubes 8 extending across the gas pass formed 35 by the flue, and connected at their opposite ends to a plurality of headers 9. These headers are arranged in groups as plainly shown in Figs. 2, 3 and 4. In these figures the groups are shown as each comprising 40 a pair of headers placed close together and with sufficient space between the headers of adjacent groups to permit the passage of a tube 8'. The tubes are arranged in transverse rows and their ends are disposed in 45 tube holes in the faces of the headers, the ends of the tubes being bent as plainly shown in Fig. 3, so that the greater portion of the tube lengths are substantially uniformly spaced apart in the row, and this 50 spacing is preferably less than a tube dia-

meter or no greater than such a diameter. The tubes in adjacent rows are staggered, as plainly shown.

In each header there are shown two longitudinal rows of tube holes, the holes in each row forming a substantially straight line longitudinally of the header. In each of these rows the tubes are arranged in pairs with a space between the pairs sufficient to permit passage of one of the tubes 8', so that when a tube in any row is to be removed or replaced, it may be easily moved into a space 10 between adjacent transverse rows, and then moved horizontally or transversely with respect to the headers into the space between groups of headers. The tubes in one row have their ends bent as indicated at 11 and 12, one tube end being bent more than the other so as to bring the tubes in the longitudinal row in staggered relation with respect to each other. In the other longitudinal row of the same header the tube ends are bent as indicated at 13 and 14, the bend 13 being a reverse bend and the bend 14 being a simple bend or in one direction only. By this arrangement the staggered effect is obtained in all rows, and at the same time the tube ends may enter the cylindrical face 15 of a header substantially normal thereto and also directed towards a handhole 16 provided on the opposite side of a header. Such handholes may be provided with the usual fittings 17. This method of bending the tube ends also lends itself to the arrangement of headers shown, two of the tube ends 11 and 12 being used on headers which are on opposite sides of the space between groups, while the ends of the form indicated at 13 and 14 are used on the adjacent parts of headers 35 in a group. The result is a substantially uniform spacing of tubes completely across the bank formed by a plurality of groups of headers and their associated tubes.

I claim:—

1. In a heat transfer device, a gas pass, a plurality of headers on each side of the pass and connected by tubes extending thereacross, the headers on one side of the pass being disposed in groups spaced apart, with

the headers in each group closely adjacent each other, and with some of the tubes bent at their ends to bring them opposite the space between said groups.

5. 2. In a heat transfer device, a gas pass, a plurality of headers on each side of the pass and connected by tubes extending therethrough, the headers on one side of the pass being disposed in groups spaced apart, with 10 the headers in each group closely adjacent each other, with some of the tubes bent at their ends to bring them opposite the space between said groups, the tubes connected to headers in adjacent groups being arranged in rows extending transversely of the headers, and the tubes in one of said rows being substantially uniformly spaced.

3. In a heat transfer device, a gas pass, a plurality of headers on each side of the pass 20 and connected by tubes extending therethrough, the headers on one side of the pass being disposed in groups spaced apart, with the headers in each group closely adjacent each other, with some of the tubes bent at their ends to bring them opposite the space between said groups, the tubes connected to headers in adjacent groups being arranged in rows extending transversely of the headers, the tubes in one of said rows being substantially uniformly spaced, and the tubes 30 in adjacent transverse rows being staggered with respect to each other.

4. In a heat transfer device, a gas pass, a plurality of headers on each side of the pass 35 and connected by tubes extending therethrough, the headers on one side of the pass being disposed in groups spaced apart, with the headers in each group closely adjacent each other, and with some of the tubes bent 40 at their ends to bring them opposite the space between said groups, the tubes connected to headers in adjacent groups being arranged in pairs of rows extending transversely of the headers.

45. 5. In a heat transfer device, a gas pass, a plurality of headers on each side of the pass and connected by tubes extending therethrough, the headers on one side of the pass being disposed in groups spaced apart, with 50 the headers in each group closely adjacent each other, and with some of the tubes bent at their ends to bring them opposite the space between said groups, the tubes connected to headers in adjacent groups being 55 arranged in pairs of rows extending transversely of the headers, the tubes in each row being spaced apart a distance less than a tube diameter and the distance between adjacent pairs of rows exceeding a tube diameter.

60. 6. In a heat transfer device, a row of headers arranged in pairs with the two headers in each pair closely adjacent each other and the pairs spaced apart in the 65 row, the headers in each pair having curved

faces with two longitudinally extending rows of tube holes therein, the tubes having their ends entered in said holes, the tube ends entering adjacent rows of holes in the two headers being alternately bent in reverse and simple bends, and the tubes entering the other rows of holes being alternately bent in the same direction but in different amounts.

7. In a heat transfer device, a row of 70 headers arranged in pairs with the two headers in each pair closely adjacent each other and the pairs spaced apart in the row, the headers in each pair having curved faces with two longitudinally extending 80 rows of tube holes therein, the tubes having their ends entered in said holes, the tube ends entering adjacent rows of holes in the two headers being alternately bent in reverse and simple bends, and the tubes entering the other rows of holes being alternately 85 bent in the same direction but in different amounts, said header faces being curved and the tube ends entering said holes substantially normal to the faces.

8. In a heat transfer device, a gas pass, a plurality of headers on each side of the pass and connected by tubes extending therethrough, the headers on one side of the pass being disposed in groups spaced apart, with the headers in each group closely adjacent each other, and with some of the tubes bent at their ends to bring them opposite the space between said groups, said space between the groups of headers being greater than a tube diameter.

DAVID S. JACOBUS.
